UNITED STATES PATENT OFFICE

EDWIN J. ELTING, OF CHICAGO, ILLINOIS

DESIGN FOR A TUBE

Application filed March 12, 1930. Serial No. 34,832. Term of patent 7 years.

To all whom it may concern:

Be it known that I, EDWIN J. ELTING, a citizen of the United States of America, residing at Chicago, in the county of Cook and State of Illinois, have invented a new, original, and ornamental Design for Tubes, of which the following is a specification, reference being had to the accompanying drawing, forming part thereof.

The figure is an elevational view of a tube, square in cross section, showing my new design on one face but the same design is contained on the other faces.

I claim:

The ornamental design for a tube, as shown and described.

In witness whereof I affix my signature.

EDWIN J. ELTING.
